George F. Pippy INVENTOR.

BY O. V. Thiel

ATTORNEY.

UNITED STATES PATENT OFFICE.

GEORGE F. PIPPY, OF EAST ORANGE, NEW JERSEY, ASSIGNOR TO AMERICAN THROTTLE COMPANY, INC., OF NEW YORK, N. Y.

MULTIPLE THROTTLE FOR LOCOMOTIVES.

Application filed June 25, 1927. Serial No. 201,502.

This invention relates to multiple throttles for locomotives of the general type disclosed in United States Patent Reissue 16,285 to Ray M. Brown, and has for its purpose the provision of an improved valve and mechanism for operating such throttles.

The invention is illustrated in the accompanying drawings, Fig. 1 of which is a longitudinal section of the forward upper portion 10 of a locomotive equipped with my improved device, Fig. 2 being an enlarged view of a portion of Fig. 1, Fig. 3 being a sectional view on line 3—3 of Fig. 1, and Fig. 4 being a modification on the same scale as Fig. 2.

15 Throttles of this multiple type are well known, and only as much of the locomotive is, therefore, shown in the drawings to make clear the relative position of the improved device.

20 1 is the outer boiler sheet; 2 the front flue sheet, and 3—3 flues extending back from the latter toward the fire-box. The smoke-box 4 is equipped with the stack 5. The superheater header 6 has the usual transverse chamber 25 7 into which saturated steam is delivered from the steam space of the boiler through the dry pipe 8. From the transverse chamber 7 extend forward the usual subsidiary chambers or fingers 9 to which are secured the ends 30 10—10 of the tubular superheater elements 11—11. The other ends of these tubular elements are connected to subsidiary chambers 12—12 which are in alternate relation to the subsidiary chambers 9—9 and communicate 35 by means of the upward passages 13—13 with the transverse chamber 14.

It was formerly usual practice to control the flow of the steam by means of a throttle located at the inlet of dry pipe 8, but it is now 40 becoming common to place the controlling throttle between the outlet of the superheater and the steam pipes. This has certain advantages which are well recognized. Instead of having one or two large throttles, 45 however, to control the steam flow, the advantage of a comparatively large number of rather small valves has impressed itself on the locomotive engineering world, and the use of such a multiple throttle control in the 50 location mentioned is becoming quite prevalent.

In the present case, these valves 15—15 are arranged in a line transverse to the smoke-box as will be clear from Fig. 3. Fig. 1 shows 55 only one of the valves. The valve housing 16

which is in effect a long transverse chamber extending from side to side of the smoke-box in its upper part is divided into an upper space 14, a middle space 17 and a bottom space 18 by means of the partitions 19 and 20. 60 As mentioned above, steam from the superheater is delivered into the top compartment 14 by the risers 12. Partition 19 is provided with a series of ports controlled by the poppet valves 15. These valves seat in the direction 65 of the steam flow and are single seated. To balance them the lower partition 20 is provided with the cylindrical apertures 21 in which reciprocate the balancing pistons 22. The balancing steam is admitted into the 70 balancing chamber 18 by means of a smaller balancing throttle 23. This balancing valve is, as will be more fully explained further on, opened in advance of the others and admits steam into chamber 18, thereby equalizing the 75 pressure on the top and bottom of the valves 15.

The steam reaches the steam chests through the two steam pipes 24—24 which are in communication with the middle space 17. 80

My invention relates to the mechanism for operating the throttles. It has been the practice heretofore to raise these throttles by means of fingers or cams secured to a transverse shaft which can be rocked or rotated through 85 an angle from the cab. My invention does not depart from this general method of valve operation, but involves an improvement therein. The shaft is shown at 25. It has a bearing 26 at one end of the heater and a 90 second bearing at 27 at the opposite end, the second end extending out through the smoke-box and the outer end being provided with the arm 28 from which extends back to the cab the operating rod 29. 95

Referring particularly to Fig. 2, the lower end of the throttle 15 will be seen to be equipped with an upper collar 30 and a lower collar 31, with both of which the cam 32 contacts. This cam 32 forms a portion of the 100 member 33 which is mounted on the shaft 25 in such a manner that 25 can rotate in it. The member 33 is not keyed or otherwise secured directly to the shaft 25 but is actuated by means of the small finger 34 carried by shaft 105 25. This finger 34 comes into contact with surfaces 35 and 36, being somewhat smaller than the space separating these two surfaces. Each valve has a finger 34 corresponding to it, and these fingers are of different sizes as will 110

be clearly seen in Fig. 2 where the upper portions of fingers behind the front one can be seen above the one associated with the valve of that figure. The lower surfaces of all of 5 the fingers 34 are in line, however. As a result the opening movement of the shaft 25 will open the valves successively, while the closing movement of the shaft will close them simultaneously and positively, and when 10 they are closed they will all be held closed by their respective fingers.

The advantages of this arrangement are obvious. It provides for positive closing of the throttles and moreover presents positive 15 means for forcing the valves on their seats. It does not interfere with the successive opening of the several throttles, the advantages of which are well understood.

There may at times be some inequalities in 20 the fingers 34 or in the lower surfaces 36 arising from either faulty machining, material lodging on these surfaces, or wear. In such a case the lower surfaces of the fingers would not all be in contact with their corresponding 25 surfaces 36 when the valves are closed. Fig. 4 shows a modification to take care of such a condition. Small leaf springs 37 secured to the members 33 are interposed between the fingers 34 and the lower surfaces 36. This 30 evidently admits of certain inequalities such as those spoken of.

I claim:

1. In a multiple throttle arrangement, the

combination of a plurality of aligned valves, each equipped with surfaces pressure on 35 which will tend to open or to close the valves respectively, members adapted to exert such opening and closing pressures, a shaft provided with fingers actuating said members as the shaft is rotated, the arrangement being 40 such that the fingers actuate the members in some order other than simultaneous to open the valves, and simultaneously to close them.

2. In a multiple throttle arrangement, the combination of a plurality of aligned poppet 45 valves; a stem on each valve with surfaces adapted for engagement by a cam; a shaft parallel to said line of stems; cams mounted rotatably on said shaft and adapted to engage said surfaces; and fingers secured to the shaft 50 to engage the cams as the shaft is rotated and to give the cams rotary motion thereby moving the valves; the arrangement being such that the fingers engage the cams in some order other than simultaneous to open the 55 valves, and simultaneously to close them.

3. The combination according to claim 2, the cams being mounted on the shaft leaving free a portion of the circumference, and the 60 fingers being mounted on these free arcs.

4. The combination according to claim 2, a spring being interposed between each finger and the part of the cam engaged by it during the closing movement.

GEORGE F. PIPPY.
